UNITED STATES PATENT OFFICE.

PATRICK W. SHIELDS, OF HOMESTEAD, PENNSYLVANIA.

BOTTLING-MACHINE.

SPECIFICATION forming part of Letters Patent No. 643,915, dated February 20, 1900.

Application filed July 14, 1899. Serial No. 723,819. (No model.)

To all whom it may concern:

Be it known that I, PATRICK W. SHIELDS, of Homestead, in the county of Allegheny and State of Pennsylvania, have invented a certain new and useful Improvement in Bottling-Machines, of which improvement the following is a specification.

My invention relates to machines for filling bottles with aerated waters, either with or without a desired proportion of syrup, and closing them by a stopper when filled; and its object is to simplify and perfect the construction and facilitate and expedite the operation of machines of the general class or type referred to.

The improvement claimed is hereinafter fully set forth.

In the accompanying drawings, Figure 1 is a front view in elevation of a bottling-machine illustrating an application of my invention; Fig. 2, a side view of the same; Figs. 3 and 4, horizontal sections on the lines *a a* and *b b*, respectively, of Fig. 1; Fig. 5, a partial vertical section on the line *c c* of Fig. 4; Fig. 6, a similar section on the line *d d* of Fig. 3; Fig. 7, a partial section through the plunger of the syrup-pump, taken at right angles to Fig. 6; Fig. 8, a partial vertical section on the line *e e* of Fig. 3; Fig. 9, a front view in elevation of a bottling-machine, illustrating a structural modification of my invention; Fig. 10, a side view of the same; Fig. 11, a plan or top view; and Figs. 12 and 13 vertical sections at the lines *f f* and *g g*, respectively, of Fig. 9.

In the practice of my invention I provide a table 1, which is supported on legs or standards 2 and which carries a removable bed or base plate 3, which supports the major part of the operative mechanism. Two vertical posts or standards 4 are fixed at their lower ends to the bed-plate 3 and are connected at top by a yoke or brace 5, each of said posts carrying a stop-collar 6, which is fixed adjustably upon it by a set-screw 7. Two operating-rod 8 are fitted to slide vertically in guides 9 on the bed-plate and are connected near their upper ends by cross-bar 10, having a lateral arm or projection 11. The operating-rod 8 slide freely through openings in a U-shaped guide-brace 12, depending from the lower side of the bed-plate, and are connected at

bottom to a cross-bar 13, which is coupled by a link 14 to a treadle 15, fixed upon shaft 16, journaled in the standards 2 of the table. 55 Helical springs 17 are connected at their opposite ends to the cross-bar 13 and to the table 1, respectively, the tendency of said springs being to bring the cross-bar and operating-rod to the normal position shown in Fig. 1. 60

A collar 18 is fixed upon each of the operating-rod 8, and a carrier-block 19, which is fitted freely on the rods 8, is supported on the collars 18. A cross-bar 20, which is also fitted freely on the rods 8, normally abuts against 65 the stop-collars 6 of the posts 4, and helical springs 21 are interposed between and bear against the cross-bar 20 and carrier-block 19. A syrup-pump 22, which is provided with a suitable piston or plunger 23 and is connected 70 by a flexible hose 24 with a source of syrup-supply, is connected to and traverses with the carrier-block 19. Communication between the supply-hose 24 and the syrup-pump 22 is controlled by an inlet-valve 25, and a delivery-valve 26 controls communication between the syrup-pump and a delivery-chamber 27, from which chamber a passage 28 leads into a delivery or discharge passage 29, formed in a presser 30, which is fixed centrally in the carrier-block 19. The passage 28 is prolonged 75 beyond the delivery-passage 29, as shown in Figs. 3, 4, and 5, and is provided with an air-escape valve 49, which is normally held seated by a spring 50, but which will be opened 80 automatically to permit the release of air if the pressure exceeds the tension of the spring or may be unseated by the operator, as desired, by the application of hand-power to its stem 51. 90

The delivery-chamber 27 communicates with a water-valve chamber 31, to which aerated water is supplied from a reservoir through a flexible hose 32, communication between the supply-hose 32 and the chamber 31 being controlled by a water-valve 33, fixed upon a vertical stem 34. The delivery-passage 29 is enlarged at its lower end to receive the neck of the bottle 35, which is to be filled, and is provided with a rubber gasket or packer 36, which serves to make a tight joint between said passage and the bottle while the latter is being filled. A rod 37 passes through the delivery-passage 29 and is provided with a

hook 38 on its lower end, which engages the loop 39 on the upper end of the wire 40, to which the stopper 41 of the bottle is connected. The upper end of the rod 37 is coupled by a 5 pin 42 to the cross-bar 20, the pin 42 being set at an angle with a horizontal plane in the jaw or clevis of the rod, as shown in Fig. 8.

The piston or plunger 23 of the syrup-pump is actuated by an arm 43, fixed to the cross-bar 10 and engaging a strap 44, connected to the piston 23. In order to enable the quantity of syrup delivered by the pump to be graduated as desired, the strap 44 and piston 23 are connected by a pin 45, passing through 10 a horizontal slot in the strap, as shown in Fig. 7, and by a pin 46, which is insertible transversely to the pin 45, in holes at different levels in the strap. It will be seen that the nearer the pin 46 is placed to the pin 45 the 15 greater will be the stroke of the piston, and vice versa, and that consequently the volume of syrup delivered at each downward traverse of the piston may be varied within determined limits, as desired.

25 In the operation of the machine the bottle 35, which is to be filled, is placed upon a removable plate 47 on the bed-plate, or if the bottle be of greater than ordinary size the plate 47 is removed and the bottle placed in a 30 receptacle 48, projecting downwardly from the bed-plate. The bottle is set in line axially with the presser 30. The operator then depresses the treadle 15, and thereby imparts downward movement to the connected operating-rod 8 and cross-bar 10. The springs 35 21, which are normally compressed by the greater tension of the springs 17, move the carrier-block 19 downwardly in accordance with the downward movement of the operating-rod 8 until the gasket 36 comes in contact with the mouth of the bottle, against which the gasket is pressed, thereby making a tight joint while the bottle is being filled. The operator then further depresses the 40 treadle, and the continued downward movement of the cross-bar 10 operates the piston 23 of the syrup-pump, supplying the desired volume of syrup, and the projection 11 of the cross-bar 10 strikes the stem 34 of the water-valve 31, thereby admitting aerated water, the supply of which is continued until the 45 bottle is filled. When the cross-bar 10, which is fixed to the operating-rod 8, comes into contact with the cross-bar 20, which is loose thereon, it moves the latter downwardly, and the inclined pin 42 swings the hook outwardly into the position shown in Fig. 8, so that it 50 will pass the loop 39 of the stopper-wire in its downward movement.

55 60 Upon the relief of pressure upon the treadle the springs 17 move the operating-rod 8 upwardly and the springs 21 move the cross-bar 20 upwardly, the latter raising, in its movement, the stopper 41, which is connected by the hook 38 to the rod 37, and bringing the stopper into position to close the mouth of the bottle, the cross-bar 20 continuing its

movement until arrested by the stop-collars 6. The upward movement of the cross-bar 10 releases the pressure of the projection 11 70 on the stem of the water-valve 33 and the latter is closed by its spring, and said movement also raises the piston 23 of the syrup-pump into position for the next operation. The continued upward movement of the operating-rod 8 raises the carrier-block 19, by 75 means of the collars 18, and compresses the springs 21, so that they will be under the tension requisite to act on the carrier-block in the next operation, and when the cross-bar 20 comes into contact with the stop-collars 6 the inclined pin 42 again moves the hook 38 laterally and releases it from the stopper-wire.

Figs. 9 to 13, inclusive, illustrate the essential features of my invention under such modifications of structural detail as adapt it for application in machines of existing constructions. As in the instance first described, two operating-rod 8 are fitted to slide vertically in guides 9, fixed upon the table 1, and are connected to a treadle 15 and returned to normal position by springs 17. The upper ends of the operating-rod are connected by a cross bar or head 10, which, as in the former instance, actuates the piston 23 of the syrup-pump and unseats the water-valve 33, and also, as will be presently described, forces the stopper 41 into position for closing the bottle 35 after the same has been filled, the 95 cross-bar 20 and hook-ended rod 37 being dispensed with. The syrup-pump 22, water-valve chamber 31, and presser 30 are, as in the instance first described, connected to and traverse with a carrier-block 19, which is fitted 100 freely on the operating-rod 8 and rests on collars 18 fixed thereon.

The spring 21, through which downward movement is imparted to the carrier-block 19, is fitted in a chamber formed centrally in the cross-bar 10 and fitting a central cylindrical projection on the carrier-block, said spring being thus interposed between and bearing at its ends on the cross-bar and carrier-block, with the same operative effect as in the former 110 instance. A rod or stem 37^a is fixed to the cross-bar 10 and passes freely through the carrier-block in line axially with the delivery-passage 29 thereof, said stem serving in the 115 final portion of its downward traverse to force the stopper 41, which is fitted in the upper end of said passage, into the neck of the bottle to effect the closure thereof.

The piston 23 of the syrup-pump is connected with the cross-bar 10, by which it is 125 actuated, through the intermediation of a spring 43^c, in order to admit of a limited degree of further downward traverse of the cross-bar 10 after the piston has been brought to the limit of its downward stroke, such 130 further traverse being employed to force the stopper 41 to position for closing the bottle. To this end the spring 43^c is interposed between the bottom wall of the piston 23 and a

follower-plate 43^b, which plate is secured upon the lower end of a rod 43^a, the upper end of which is connected to an arm 43 on the cross-bar 10. The valve mechanism of the syrup-pump and its relation to the water-valve chamber 31 and discharge-passage 29 accord in all substantial particulars with the corresponding features of the construction first herein described.

10 The water-valve 33 is, as in the instance first described, unseated by the cross-bar 10 in the downward movement of the latter, an interposed mechanism being provided whereby the required further traverse of the cross-bar after the unseating of the valve is permitted without causing or permitting the closure or reseating of the valve. A mechanism suitable for this purpose is shown in Figs. 11 and 13, the same consisting of a bell-crank 15 or elbow lever 34^a, which is journalled in a bracket 34^b, fixed to the carrier-block 19, and has its upper arm coupled to the stem 34 of the water-valve 33. The lower arm of the bell-crank lever is coupled to a bar 34^d, which 20 is fitted to slide longitudinally in a guide in the bracket 34^b and is jointed to a bar 34^c, having an inclined end face abutting against a corresponding face on the lower end of a pushing-bar 11^a, which projects downwardly 25 from the cross-bar 10. In the downward traverse of said cross-bar the pushing-bar moves the connected bars 34^d 34^c to the left, thereby rocking the bell-crank 34^a in its bearings and unseating the water-valve. When 30 the cross-bar 10 has made a traverse corresponding with the full stroke of the syrup-pump piston, a recess in the face of the pushing-bar 11^a is brought opposite the end of the bar 34^d, thereby relieving its pressure on the latter, and the spring of the water-valve thereupon closes said valve. In the upward traverse of the cross-bar 10 the bar 34^d is turned 35 upwardly sufficiently far to be released from the recess of the pushing-bar 11^a and thereafter drops by gravity to the normal position shown in Fig. 13. A spring may be added to insure its return, if desired.

The operation of the machine accords in all substantial particulars with that of the 50 construction first described. The stopper 41 is fitted in the upper end of the discharge-passage 29, and the bottle 35 is placed upon the table below and in line axially with said passage. The operator then depresses the treadle 15, and the spring 21 being relieved from the tension of the spring 17 forces the carrier-block 19 downwardly, and the presser 30 on its lower end presses the gasket 38 55 against the bottle, making a tight joint therewith while it is being filled. Further depression of the treadle and corresponding movement of the cross-bar 10 actuates the piston of the syrup-pump and unseats the water-valve. When the bottle is filled, the treadle 60 is still further depressed, and the rod 37^a is caused to press upon the stopper 41 and forces it into closing position in the neck of the bot-

tle. Upon the relief of pressure on the treadle the parts are returned to normal position by the springs 17, as in the former instance, the 70 spring 43^c being released from compression by the upward movement of the cross-bar 10, and the spring 21 being subjected to compression in readiness for the next succeeding operation by the upward movement of the 75 carrier-block 19.

It will be obvious to those skilled in the art that while for the purpose of preventing unbalanced lateral strains and attaining the most advantageous application of the power 80 of the operator two operating-rods have been herein described and shown, the essential features of my invention might without variation of operative principle be embodied in a construction in which only one operating-rod is employed, and such a construction I 85 therefore desire to include as a mechanical equivalent for that herein set forth and claimed.

My invention presents in practice the substantial advantage of enabling all the movements of the operating members to be effected by the foot of the operator instead of, as in prior constructions, requiring him to manipulate a hand lever or levers in addition thereto. 95 The hands of the operator are consequently left free, and he is enabled to insert and remove the bottles and stoppers, and the operation of bottling is facilitated to such an extent that the services of an assistant heretofore required may be dispensed with. The apparatus is of simple and comparatively-inexpensive construction, and the working parts are free from liability to breakage or derangement in service.

100 I claim as my invention and desire to secure by Letters Patent—

1. The combination, in a bottling-machine, of two operating-rods, a carrier-block supported freely thereon, a water-valve working in a chamber carried by the carrier-block, a cross-bar on the operating-rods, a spring interposed between and bearing on the carrier-block and cross-bar, means carried by the operating-rods for unseating the water-valve, a treadle connected to the operating-rods, and a spring acting on the operating-rods in reverse direction to that of the application of power to the treadle.

2. The combination, in a bottling-machine, of two operating-rods, a carrier-block supported freely thereon, a syrup-pump carried by the carrier-block, a cross-bar on the operating-rods, a spring interposed between and bearing on the carrier-block and cross-bar, means for actuating the piston of the syrup-pump by movement of the operating-rods, a treadle connected to the operating-rods, and a spring acting on the operating-rods in reverse direction to that of the application of power to the treadle.

3. The combination, in a bottling-machine, of two operating-rods, a carrier-block supported freely thereon, a water-valve and syr-

- up-pump connected to a chamber carried by said block a presser fixed to the carrier-block in position to be applied to the mouth of a bottle a conduit connecting said chamber and presser, a cross - bar on the operating- rods, a spring interposed between and bearing on the carrier - block and cross - bar, a treadle connected to the operating- rods, and a spring acting on the operating- rods in reverse direction to that of the application of power to the treadle.
4. The combination, in a bottling-machine, of two operating- rods, a carrier-block supported freely thereon, a presser fixed to the carrier-block in position to be applied to the neck of the bottle, a syrup-pump and water- valve supported by the carrier-block and connected to said presser a cross-bar on the operating- rods, a spring interposed between and bearing on the carrier-block and cross- bar, a rod, actuated by the cross-bar, for fixing a stopper in position in a bottle, a treadle connected to the operating- rods, and a spring acting on the operating- rods in reverse direction to that of the application of power to the treadle.
5. The combination, in a bottling-machine, of two operating- rods, a carrier-block supported freely thereon, a water-valve working in a chamber carried by the carrier-block, a syrup-pump connected to the carrier-block, valves controlling communication between the water - valve chamber and syrup - pump and a common discharge or delivery passage, a cross-bar on the operating- rods, a spring interposed between and bearing on the carrier-block and cross-bar, means for unseating the water-valve by movement of the operating- rods, means for actuating the syrup- pump by movement of the operating- rods, a treadle connected to the operating- rods, and a spring acting on the operating- rods in reverse direction to that of the application of power to the treadle.
45. 6. The combination, in a bottling-machine, of two operating- rods, a carrier-block supported freely thereon, a treadle connected to and adapted to impart downward movement to the operating- rods, a spring connected to and adapted to impart upward movement to the operating- rods, a water-valve working in a chamber carried by the carrier - block, a syrup-pump connected to the carrier-block, valves controlling communication between the water-valve chamber and syrup - pump and a common discharge or delivery passage, a presser fixed to the carrier-block in position to be applied to the neck of a bottle, a rod for fixing a stopper in position in a bottle, a cross-bar on the operating- rods, a spring interposed between and bearing on the carrier-block and cross-bar, and means for actu-

ating the water-valve, the syrup-pump piston, and the stopper-fixing rod by the movement of the operating- rods, these members 65 being combined for joint operation to first close the joint between the delivery-passage and presser and the mouth of a bottle, to thereafter charge the bottle with aerated water and syrup, to thereafter fix the stopper 70 in the bottle, and to thereafter release the presser from the bottle.

7. The combination, in a bottling-machine, of two operating- rods, a carrier-block supported freely thereon, a syrup-pump carried 75 by the carrier-block, a cross-bar on the operating- rods, a spring interposed between and bearing on the carrier-block and cross-bar, means for actuating the piston of the syrup-pump by movement of the operating- bars, 80 means for varying the length of stroke of the piston of the syrup-pump, a treadle connected to the operating- rods, and a spring acting on the operating - rods in reverse direction to that of the application of power to the treadle. 85

8. The combination, in a bottling-machine, of two operating- rods, a carrier-block supported freely thereon, a presser fixed to the carrier-block in position to be applied to the mouth of a bottle, a cross bar or head fixed 90 to the operating- rods, a cross-bar fitting freely on the operating- rods between the fixed cross- bar and the carrier-block, fixed stops against which said freely-fitting cross-bar normally abuts, a spring interposed between and bearing on the freely-fitting cross-bar and the carrier-block, a rod passing freely through the carrier-block and presser and having a hook on its lower end to engage the wire of a bottle-stopper, and a pin coupling said rod to the 100 freely-fitting cross-bar, said pin being set at an angle to a horizontal plane and passing through a horizontal opening of greater diameter in said cross-bar. 95

9. The combination, in a bottling-machine, 105 of a carrier-block, having a delivery or discharge passage and a presser surrounding the lower end of said passage, a syrup-pump and a water-valve chamber, each provided with a connection for a flexible hose and fixed 110 to the carrier-block, a valve controlling communication between the hose connection of the water-chamber and the delivery-passage, an inlet-valve controlling communication between the hose connection of the syrup-pump 115 and the cylinder thereof, and an outlet-valve controlling communication between the cylinder of the syrup-pump and the delivery passage.
